UNITED STATES PATENT OFFICE.

JAMES McNAMARA, JR., OF PORTLAND, OREGON.

PLASTERER'S MITERING PLANE.

Application filed January 28, 1924. Serial No. 639,123.

To all whom it may concern:

Be it hereby known that I, JAMES McNAMARA, Jr., a citizen of the United States, and a resident of Portland, in the county of 5 Multnomah and State of Oregon, have invented a new and useful Plasterer's Mitering Plane, of which the following is a specification.

This invention relates generally to the 10 plastering art, and more particularly to the construction of miter corners in mouldings made of plaster.

The object of my invention is to provide an exceedingly simple and efficient mitering 15 plane, which is in reality a four-sided plane for working the concave and convex surfaces of a plaster moulding accurately to the extreme corner of the miter.

Another object is the construction of a 20 plane so that its cutting tool can readily be sharpened and adjusted with the use of ordinary tools.

Still another object is the construction of the plane in a manner that the bit will cut 25 on either of two sides.

I accomplish these results in the manner set forth in the following specification and illustrated in the accompanying drawing, in which:—

30 Figure 1 is a side elevation of the plane with its mid-section broken away to reduce its length. Figure 2 is a plan of Figure 1 with a portion broken away along the line 2—2 in Fig. 1. Figure 3 is a left end elevation of Figure 1. Figure 4 is a right end elevation of Figure 1. Figure 5 is a portional side elevation of a modified form of the device of which Figure 6 is a left end elevation. Figure 7 is a portional side elevation of still another modification of the 35 device, of which Figure 8 is a left end elevation.

Similar numbers of reference refer to the same parts throughout the several views.

40 Referring in detail to the drawing, I have constructed my device in the form of a parallelogram having two long sides 10 and 11. The side 10 is flat and the side 11 is rounded, while the short sides 12 and 13 are flat and 45 form acute angles with the sides 10 and 11, in which are placed the large fillets 14 which are grooved along the center lines of the acute angles, above referred to, on both sides of the fillets 14 to receive the slotted bits 15 and 16. Screws 17 are threaded into the fil-

lets 14 and provide adjustment for the bits 15 and 16.

The faces 18 of the bits 15 and 16 project slightly beyond the face of the plane to give the required set. Cross braces 19 add 60 stiffness to the long sides 10 and 11, and at the same time provide better grips for the hands.

In Figures 5 and 6 I have illustrated a bit 20 which is provided with a dovetail 21 65 with adjusting screw 22. In Figures 7 and 8 the blade 23 is made double handed and provided with countersunk holes for the stove bolts 24.

The sides 10 and 11 are made somewhat 70 heavier near the points in the two modifications, just described, to permit the reception of the blades. It is preferable to slot the holes for the stove bolts 24 in the side 10 to permit of adjustment for the bit 23. If desired a small piece of paper or other material may be used to fill the gap between the blade and the shoulder on the side 10.

The operation of my device is as follows: 75 The blades 15 are set with their cutting faces slightly projecting over the adjacent sides and the appropriate face 10, 11, 12 or 13 is placed against the moulding and the two moved backwardly and forwardly until the point of the blade 15 has cut away the 80 desired amount of material. This action tends to plane off the high spots and inequalities right up to the corner of the miter.

The sizes of the plane, formations of the 85 faces and methods of fastening and adjusting the bits can, of course, be varied greatly to suit the convenience or demand for a special tool without departing from the spirit of my invention.

I am aware that planes have been constructed employing a blade on the nose of the plane and using only one face of the plane, I therefore do not claim my device broadly but intend to cover only such forms 90 and modifications as fall fairly within the appended claims:

1. A plasterer's plane consisting of a quadrilateral frame having two opposite long sides, one of which is rounded and the 1 other straight, and having two short sides forming acute angles at opposite corners of said frame; and an adjustable bit placed across the edges of said acute angles.

2. A plasterer's plane consisting of a four

26-1053

- faced frame forming a parallelogram and having opposite acute angled corners, said frame having grooves cut into its sides through said corners, in combination with 5 cutting blades fitting into said grooves and having the cutting edges of said blades extending past the adjacent faces at the aforesaid corners of said frame.
3. A plasterer's plane consisting of a 10 hollow four-sided frame in the form of an angled parallelogram whose short sides form acute angles at opposite corners of said frame, one long side of said frame having a rounded face and the other three sides 15 having straight faces; and a pair of cutting blades adjustably secured along the center line of said acute angled corners.
4. A plasterer's plane consisting of a hollow parallelogram-shaped frame having one rounded and one straight side and having 20 two short sides forming oblique angles to said long sides, said frames having large fillets formed in each of its pointed ends, and having intermediate cross braces between said long sides, said fillets having 25 grooves formed therein along the center lines of their respective angles; and cutting blades for said grooves each of which consists of a U-shaped blade whose closed sharpened edge projects somewhat past the point 30 of intersection of the adjacent sides of said frame; and a screw in said fillet adapted to furnish adjustment for said blade.

JAMES McNAMARA, JR.
